UNITED STATES PATENT OFFICE.

LEONARD TILTON, OF BROOKLYN, NEW YORK.

CANCELING-STAMP.

SPECIFICATION forming part of Letters Patent No. 237,068, dated January 25, 1881.

Application filed October 25, 1880. (No model.)

To all whom it may concern:

Be it known that I, LEONARD TILTON, of Brooklyn, in the county of Kings and State of New York, have invented a new and useful Improvement in Canceling-Stamp, of which the following is a specification.

My improvements relate to hand-stamps for stamping letters and checks, and for similar purposes.

10 The object of the invention is to furnish a stamp that can be readily manipulated to bring it to the desired position on the bed, and which shall give a uniform pressure in stamping to insure plain marking.

15 In the accompanying drawings, forming part of this specification, Figure 1 is a side elevation of the canceling-stamp and stand, the tubular post being partially in section. Fig. 2 is a section, vertically, of the head that carries the plunger, with the stamp and pad shown in elevation in their raised position. Fig. 3 is a front view of the pad-carrying arm, as seen in the depressed position of the stamp. Fig. 4 is a perspective view of the pad and ink-box; and Fig. 5 is a horizontal section of the plunger-head on line xx of Fig. 2.

Similar letters of reference indicate corresponding parts.

20 A is the stand of the apparatus, fitted for being attached to a table or other support, on which the bed or platen a is also placed. The stand consists of a circular plate, b , formed with a central aperture and having undercut sides, a tubular post, c , having a semi-spherical base that sets within the aperture of plate b , and a flanged collar, d , around post c , to which the sleeve is secured by a set-screw, a' . In the sleeve d three set-screws, d' , are fitted to bear on plate b , so that the post c is thereby held in place and can be adjusted to level the stamp. In the tubular post c is a standard, e , the lower end of which rests on a steel plate, f , that is secured over the lower end of post c , so that the standard is sustained by the 35 post and is free to turn therein.

40 g is a hub or collar secured on standard e by a set-screw to permit vertical adjustment.

h is a horizontal arm secured on hub g and extending at both sides of the hub.

45 i' is a right-angled arm secured to the forward end of arm h , so that its upper end ex-

tends horizontally in direction from the arm h , and in the same vertical plane, or nearly so. To the rear end of arm h is fixed a cross-piece that carries two wheels or rollers, $i i$, one above the other, which rollers have flanged peripheries.

k is the head carrying the stamp proper, which head is attached upon an arm, l , that is formed with, or has attached to it, a vertical extension, m , that carries a flanged wheel or roller, n , resting on the horizontal portion of arm i' . The arm l extends between the two rollers $i i$, so that said arm l and its attached parts are supported by the rollers $i n$. A piece, o , attached on arm h and extending over arm l , serves, in connection with the flanges of the rollers, to prevent side movement of arm l . With this construction the arm l and head k , carrying the stamp, can turn with hub g and standard e , and the arm l also be moved in and out, thereby permitting the stamp to be brought over any portion of the bed a , as required. The stamp being once properly leveled will come squarely upon the bed at every blow, thus insuring perfect marking; and the stamp may also be used with great rapidity. The head k is fitted with a tube, k' , which rests by flanges on the upper end of the head, and through the tube k' passes the plunger p of the stamp.

To the lower end of tube k' a collar, q' , is attached by set-screws, which collar carries the ink box and pad r , while to the lower end of the plunger is fixed the clamp q for receiving the die. The plunger is provided with a rib or feather, p' , which extends within a slot in tube k' , so that the tube shall turn with the plunger, thereby permitting the die to be turned, as required, and retaining the pad in proper relation thereto. The plunger is thus also made capable of vertical movement, and is raised by a spiral spring fitted around it above head k .

The ink-box is carried by an arm, s , that is adjustably connected to collar q' . The lower end of this arm is provided with a tube, s' , through which passes the pivot-pin r' , that has attached to one of its ends a frame, t , that is adapted for receiving the ink-box.

As shown most clearly in Fig. 3, the bottom of frame t is formed with dovetail slots that

receive lugs t' formed on the bottom of the ink-box. The box is to be inserted endwise, and is formed with a lug, r^2 , that extends through a slot in the side of frame t ; and a latch, t^2 , is provided on the frame to engage with lug r^2 , to retain the box from moving endwise, thereby preventing disengagement of lugs t' from the slots. The frame t is slotted at its side, or provided with a bent arm, u , forming a slot, and the die-clamp q is fitted with an adjustable plate, r , on which a roller, w , is fitted in position for entering the slot of frame t . When the plunger is in its upward position roller w is within the slot, and thereby retains the ink-box in the horizontal position, with the pad against the die. As the plunger descends the roller carries the ink-box and pad

to one side, as shown in Fig. 1, and the box is again raised as the plunger rises.

Having thus described my invention, I claim 20 as new and desire to secure by Letters Patent—

In canceling stamps, the means for sustaining and obtaining universal movement consisting of the stamp-carrying arm l , provided 25 with roller n , the hub g , provided with the arms h i' , and rollers i i , and the swiveling standard e , carrying the hub, combined for operation substantially as shown and described.

LEONARD TILTON.
